UNITED STATES PATENT OFFICE.

ALBERT WANNER, JR., OF HOBOKEN, NEW JERSEY.

DESIGN FOR A MIRROR-FRAME.

SPECIFICATION forming part of Design No. 25,314, dated March 31, 1896.

Application filed October 14, 1895. Serial No. 565,697. Term of patent 7 years.

To all whom it may concern:

Be it known that I, ALBERT WANNER, Jr., of Hoboken, in the county of Hudson and State of New Jersey, have invented and produced a new and original Design for a Mirror-Frame, of which the following is a full, clear, and exact description.

Reference is to be had to the accompanying drawing, forming a part of this specification, which represents a front view of a folding mirror-frame having ornaments embodying my new design, the sides of the figure having two series of the ornaments applied.

The design relates to ornaments to be applied to frames and other articles and is especially designed to be applied as a border.

The leading feature of my design consists in an ornament comprising the foliate scroll

a and the smaller floriate scroll *c*, twining with the scroll *a*.

Another feature of the design is the device *b*, presenting the appearance of a conventionalized leaf, the said device *b* having a plurality of members departing laterally, the members being smaller toward the top.

Another feature of my design is the ornament *d*, the same comprising a scrolled frame or border, lattice-work within the frame, and a floriate center within the lattice-work.

I claim—

The design for a mirror-frame herein shown.

ALBERT WANNER, JR.
